J. M. B. attorney

UNITED STATES PATENT OFFICE.

WALTER D. KAHN, OF NEW YORK, N. Y., ASSIGNOR TO IMPORT SALES COMPANY, OF NEW YORK, N. Y., A CORPORATION OF NEW YORK.

PORTABLE ELECTRIC LIGHT.

1,264,525.

Specification of Letters Patent. Patented Apr. 30, 1918.

Application filed August 16, 1917. Serial No. 186,537.

To all whom it may concern:

Be it known that I, WALTER D. KAHN, a citizen of the United States, and a resident of the city, county, and State of New York, have invented an Improvement in Portable Electric Lights, of which the following is a specification.

My invention relates to a portable electric light operated from dry cells and sometimes referred to as a flash-light, which comprises a container, frequently made of metal, a reflector mounted within the container and carrying a lamp, a lens by which the reflector is usually retained in place, a dry battery and suitable switching mechanism.

My invention relates more particularly to improvements in the switching mechanism for this type of lamp and aims to produce a switching mechanism of simple and inexpensive construction, which is positively and easily operated, is capable of easy repair and adjustment and is so arranged as to prevent short-circuiting of the battery by metallic objects which may be in contact with various portions of the container. My invention is particularly applicable to flash-lights having a metallic case, but it will be understood that it may be applied to flash-lights having a case of fiber or other insulating material.

80 In the drawings:

Figure 1 is a side view of my improved portable electric light;

Fig. 2 is a sectional view thereof;

Fig. 3 is a plan view of a portion of the switching mechanism;

Fig. 4 is a side view thereof;

Fig. 5 is a plan view of the under side thereof; and

Fig. 6 is a sectional view thereof.

40 Referring to the drawings, it will be seen that my improved portable electric light comprises a casing or container 1, which may be made of metal or insulating material, and is illustrated in the drawings as being made of metal. The container 1 contains a battery 2 and is closed at one end by means of a screw-cap 3 carrying a spring 4, which makes contact with the metallic shell

of the battery, and therefore with one pole thereof.

50 At the opposite end of the container 1 is located a lens 5 held in place by a screw-cap 6. Lens 5 bears against a reflector 7, which is provided with a screw-threaded cylindrical portion within which is mounted the lamp 8.

Located within the case is an insulating member 9 of disk shape, having a central screw-threaded aperture within which the screw-threaded end of the reflector is secured, and a notch 10 at its periphery, the purpose of which will be hereafter explained. Attached to the under side of the insulating disk 9 is a metallic member 11, which may be in the form of a cup, or may take any other suitable shape to perform the functions hereinafter described. Mounted within the metallic member 11 is a spring contact member 12, adapted to make yielding contact with one pole of the lamp 8 and electrically connected to the metallic member 11. Secured to the under side of the metallic member 11 is a second insulating member 13, preferably disk-shaped, and having a notch 14 and secured to the under side of the metallic member 11 by means of rivets, or any other suitable fastening 15. The insulating disk member 13 carries on its under side a metallic member 16, which may be attached to the disk member 13 by means of a rivet 17, or any other suitable fastening. Metallic member 16 is provided with a spring projection 18, having a projection 19 adapted to be brought into contact with the metallic member 11. Projection 18 extends through the notches 14 and 10 formed in the two insulating disk members 9 and 13.

85 Secured to the inside of the case is a switch contact-operating member 20, of insulating material, which may be operated from the outside of the case by means of a thumb-piece 21 connected to the contact-operating member by means of rivets 22, or in any other suitable manner. Contact-operating member 20 carries at its free end an enlargement which may be in the form of a

metallic piece 23 riveted thereto and adapted to coöperate with the projection 18 of the lower metallic member 16. The construction is preferably such that the projection 23 fits 5 into the depression opposite the projection 19, and thus locks the switch in the closed position. The notches 10 and 14 being in line, the switch can only be operated through movement of the switch contact-operating member 20 through said notches. This construction effectually prevents the lamp being assembled in any other except the correct 10 position, since the disks can not be put into the lamp except in such a position that the switch operating member 20 will pass into 15 the notches.

It will be noticed that it is impossible to short-circuit the battery of the improved portable electric light, since all of the exposed portions of the case are of the same 20 polarity, and it is therefore possible to make a circuit through the battery only by operation of the switch mechanism.

While I have only described one form of 25 my invention, it is obvious that it may be greatly varied without departing from its spirit, and I therefore do not intend to confine myself to the precise details shown and described.

30 What I claim is:

1. A portable electric light, comprising a member of insulating material, a reflector secured thereto, a metallic member secured to the member of insulating material and in 35 contact with one pole of the lamp, a second insulating member, a spring member mounted thereon, and means for flexing the spring member into contact with the metallic member to close the circuit of the lamp.

40 2. A portable electric light, comprising a notched disk of insulating material having an aperture, a reflector secured in said aperture, a metallic member mounted upon the disk, a lamp mounted within the reflector 45 and electrically connected to said metallic member, a second notched disk of insulating material secured to said metallic member and a second metallic member secured to said second disk and having a projection adapted 50 to be brought into contact with the first metallic member, and means, operable when the notches in the insulating disks are in alinement, for effecting such contact.

55 3. A portable electric light, comprising a member of insulating material, a cup-shaped metallic member secured thereto, a lamp mounted within said insulating member and contacting with said cup-shaped metallic member, a second insulating member secured 60 to said cup-shaped metallic member and a second metallic member carried by said second insulating member and having a projection adapted to contact with the side of said cup-shaped metallic member.

4. A portable electric light, comprising a 65 casing, an insulating member mounted within the casing and disposed transversely thereof, a metallic member carried by said insulating member and having a portion of its surface located longitudinally of the casing, a 70 second member of insulating material disposed transversely of the casing and mounted therein, a second metallic member having a portion of its length longitudinal of the casing, and a contact-operating member 75 adapted to move the longitudinally disposed portion of the second metallic member transversely of the casing into contact with the longitudinally disposed portion of the first metallic member. 80

5. A portable electric light, comprising a pair of notched disks of insulating material, a pair of metallic contact members carried by said disks and normally insulated from one another, a lamp in contact with one of 85 said contact members, a battery in contact with the other of said metallic contact members, and a contact controlling member movable within the notches in said disks and adapted to move one of said metallic contact 90 members into contact with the other.

6. A portable electric light, comprising an insulating member, a fixed metallic contact member carried thereby, a second metallic contact member, a second insulating member 95 interposed between said metallic contact members, one of said metallic members being provided with a projection adapted to be moved into contact with the other of said metallic contact members and being provided 100 with a depression, and a switch controlling member provided with a projection adapted to coöperate with the depression in said metallic switch controlling member to lock the switch controlling member in position. 105

7. A portable electric light, comprising a disk of insulating material, provided with a threaded central aperture and a notch at its periphery, a second disk of insulating material also having a notch at its periphery, a 110 metallic contact member mounted upon each of said disks, one of said metallic contact members being provided with a projection extending into the notches of both of said disks and in proximity to the other metallic 115 contact member, and a switch-controlling member adapted to coöperate with said projection to cause contact with said metallic contact members and adapted to be moved in said notches. 120

8. A portable electric light, comprising a cylindrical case, a reflector mounted therein and in contact therewith, a disk of insulating material having a central aperture in threaded engagement with said reflector, a cup-shaped metallic contact member mounted upon said disk and of smaller diameter than said case, a lamp mounted within the re- 125

flector and in contact with said metallic contact member, a second disk of insulating material attached to said metallic contact member, a second metallic contact member
5 carried by said second disk and having a projection disposed longitudinally of the case, but out of contact therewith, a battery connected to said second contact member and a contact controlling member mounted within

the case and adapted to be moved longitudinally thereto to move the projection upon said second metallic contact member into contact with the first.

In testimony whereof, I have signed my name to this specification this 6th day of 15 August, 1917.

WALTER D. KAHN.
